A technical line drawing of a mechanical assembly. It features a rectangular housing 11 with a slot on the left side. A cylindrical component 19 is inserted into the housing, showing a ribbed center 21. A lever 20 is attached to the top of the cylinder. The drawing is labeled with numbers 11, 19, 20, and 21.

UNITED STATES PATENT OFFICE

CLAUD E. FULLER, OF NEW YORK, N. Y., ASSIGNOR TO NEW YORK BRICK HANDLING CORPORATION, OF NEW YORK, N. Y., A CORPORATION OF NEW YORK

RECEIVING STATION

Application filed April 14, 1928. Serial No. 270,083.

My present invention relates to the manufacture of brick, and more particularly to an improved receiving station for use in such manufacture.

5 In the manufacture of brick, and particularly the manufacture of brick by the soft mud process, where the bricks are formed in molds and afterwards placed on a pallet and subjected to a drying operation before being 10 built into a kiln for burning, it is important to devise economical means for collecting the pallets of brick into groups before depositing the same in the drier. The open top drier has been found to be the most economical in 15 use in drying bricks under these conditions.

In connection with the operation of such a drier I have found it desirable and economical to arrange the pallets of brick in series, consisting of a plurality of layers of predetermined size. In order to collect the pallets 20 of brick in predetermined sized layers, I may employ any desired means.

I am enabled to arrange the pallets of an oncoming stream of pallets into groups of 25 any predetermined size, and with my device I arrange these groups of pallets into a series of predetermined layers, and then remove such predetermined plurality of layers simultaneously from the receiving apparatus and 30 prior to the depositing thereof in the open top drier.

The object of my invention, therefore, is an improved receiving station.

35 Another object of my invention is an improved mechanism for collecting groups of pallets of predetermined size into a series consisting of a plurality of layers.

Other objects and novel features of the construction and arrangement of parts comprising 40 the device will appear as the description of the invention progresses.

In the accompanying drawings illustrating a preferred embodiment of my invention,

45 Fig. 1 is a side elevation;

Fig. 2 is a plan view;

Fig. 3 is an end elevation looking to the right of Fig. 1;

Fig. 4 is a sectional elevation on the line 50 4—4 of Fig. 2;

Fig. 5 is a sectional elevation on the line 5—5 of Fig. 2;

Fig. 6 is a sectional elevation on the line 6—6 of Fig. 3;

Fig. 7 is a view similar to Fig. 6 but showing the parts in another position;

Fig. 8 is a section on the line 8—8 of Fig. 1;

Fig. 9 is a section on the line 9—9 of Fig. 6, and

Fig. 10 is a section on the line 10—10 of 60 Fig. 7.

Referring to the drawings, 10 designates a base, on the upper face and on each end of which are mounted rectangular frameworks 11, these frameworks being tied together by 65 cross bars 12, 13, 14 and 15. Associated with each of the rectangular frames 11 and mounted on the cross bars 13 are bearing blocks 16, there being three of such bearing blocks for each of the rectangular frames 11, and which three form a set which are in alignment with each other, and rotatably mounted in each set

is a shaft 17. In each framework 11 and at the lower end thereof, are formed guideways 75 18, and in each of such guideways is slidably mounted a bearing 19, a screw 20 being utilized to move the bearing members 19 in the guideways. In each pair of bearing members 19 is rotatably mounted a shaft 21, which

shaft is arranged parallel to and directly beneath the associated shaft 17 at the top of each framework 11. Secured to each of the shafts 17 and 21, are sprocket wheels 22, and over such sprocket wheels 22 run endless conveyor 80 chains 23. There are two of these conveyor chains 23 for each of the rectangular frameworks 11 and the pairs of chains 23 are connected together by angle irons 24. Built

out from the rectangular frameworks 11 and forming a joining member therefor, is a platform 25 on which is mounted a motor 26, connected through clutch 27 to a worm and worm wheel drive 28. The worm and worm wheel drive rotates a gear 29. On the cross bars 12 are arranged bearing blocks 30 and in the bearing blocks 30 are rotatably mounted shafts 31, such shafts being arranged parallel to each other, as clearly shown in Fig.

3. Secured to the ends of the shafts 31 are 95 gears 32, such gears being equal in diameter 100

and pitch and one of them meshing with the gear 29 above referred to. The motor 26, therefore, operates to rotate the shafts 31 in opposite directions and at the same rate of speed. Formed on the shafts 31, intermediate the ends thereof, are cranks 33, and rotatably mounted on such cranks are connecting rods 34. The ends of the connecting rods 34 are pivotally attached to the outer free end of levers 35 that are rotatably mounted on the shafts 17. Pivotally mounted on each of the levers 35 intermediate the ends thereof, is a pawl 36 which is weighted by means of a weight 37 so as to continually urge the pawl 36 inward toward the shaft 17, as clearly shown in Fig. 4. Secured to each of the shafts 17 is a ratchet 38 and the pawl 36 is adapted to engage with such ratchet 38 so as to cause an intermittent rotation of the shaft 17 in a manner to cause an intermittent upward movement of the inner or opposing reaches of the endless conveyor chains 23. Mounted on an angle iron 39 connecting the cross bars 13 is a shaft 40 on which is rotatably mounted a holding pawl 41 and a spring 42 secured to the angle iron 39, such spring constantly urging the pawl 41 into engagement with the ratchet 38 and acting as a means to prevent retrograde movement of such ratchets.

Associated with the endless conveyor chains 23 so as to deliver pallets 43 of brick 44 to opposed cross bars 23 is an endless conveyor 45 mounted on suitable framework 46 and driven through suitable gearing from a motor 47, a magnetic clutch 48 and brake 49 being interposed between the motor 47 and driving mechanism for the endless conveyor. Associated with the wiring mechanism for the motor 47 is a switch mechanism 50 and associated with the clutch 27 interposed between the motor 26 and worm wheel mechanism 28, which is also a magnetic clutch, is a switch mechanism 51. Associated with the delivery end of the conveyor 45 is a switch arm 52 and associated with the delivery end of such conveyor 45 is a switch arm 53. The switch arm 53 closes a circuit in either of its extreme positions, while the switch arm 52 closes a circuit only in one of its extreme positions.

If we assume that the groups of pallets 43 with the brick 44 thereon is just coming into engagement with the switch arm 52, then a circuit to operate the magnetic clutch 48 and magnetic brake 49 will be closed as follows: from source of power 54, conductor 55, switch arm 53, conductor 56, switch arm 52, conductor 57, energizing winding 58 of the switch 50, conductor 59, conductor 60 and back to the source of power 54. This will cause an attraction of the armature 61 of the switch 50 and the closing of the energizing circuit direct for the magnetic clutch 48 and magnetic brake 49, from source of power 54, conductor 55, conductor 62, contacts 63, 64 and armature 61, and conductor 65 through the magnetic brake 49 and magnetic clutch 48 in parallel through conductor 66, conductor 60 and back to the source of power 54. The magnetic brake 49 thereupon releases and the magnetic clutch being simultaneously operated, the constantly operated motor 47 is connected to the driving mechanism for the conveyor 45, and immediately the group of pallet 43 has passed beyond the switch arm 52, such switch arm returns to its original position, thereby breaking the circuit originally closed through. The attraction of the armature 61 of the switch 50, however, closes a holding circuit to retain the energizing circuit for the magnetic clutch 48 and magnetic brake 49 as follows: Source of power 54, conductor 55, switch arm 53, conductor 56, conductor 67, contacts 68 and 69 and the armature 61, energizing winding 58 of the switch 50, conductor 59, conductor 60, and back to source of power 54. This holding circuit will be maintained and the clutch 48 kept in operation until the group of pallets 43 have moved into proper association with the opposed pair of angle irons 23, at which time the switch arm 53 will be thrown to its other extreme position, breaking connection between the conductors 55 and 56, thereby allowing the holding circuit for the energizing coil 58 of the switch 50 to be broken and breaking the energizing circuit for the clutch and brake at the contacts 53 and 64. Immediately this circuit is broken, the magnetic clutch will be brought into play and will incidentally stop the progress of the conveyor 45. When the switch arm 53 broke the connection between the conductors 55 and 56, it immediately closed the connection between the conductors 55 and 70, such conductors 70 being connected to energizing windings 71 of the switch 51 and thence by conductor 72 to a limit switch 73 arranged at the top end of the endless conveyor 23, and thence by conductors 74 to conductor 60, and to the source of power 54. The closing of this circuit closes an energization of the winding 71 of the switch 51 and a drawing up of its armature 75. The drawing up of the armature 75 completed a holding circuit for the winding 71 as follows: source of power 54, conductor 55, conductor 76, contacts 77 and 78, armature 75, and energizing winding 71, conductors 72, limit switch 73, conductors 74, conductor 60 and back to the source of power 54. Also a circuit is closed from source of power 54, conductor 55, conductor 79, magnetic clutch 77, conductor 80, contacts 81 and 82 and the armature 75, conductor 83, conductor 60 and back to the source of power 54. This energization of the magnetic clutch 54 connects the motor 26 to the worm and worm wheel drive 28 and causes a rotation of the shafts 31 in opposite directions through one complete revolution and causes a reciprocation of the connecting rods 34 and, therefore, a step around of the shafts 17

through the space of one tooth of the ratchet 38, this being sufficient to move the opposed pair of angle irons 23, on which now rests one of the pallets 43, upward a sufficient distance 5 to bring the next succeeding opposed pair of angle irons 23 into association with the delivery end of the endless conveyor 45. Forming part of the limit switch 73 is a pivoted lever 84, which controls the switch 73 and 10 has a roller 85 at its free end that is adapted to be engaged by a cam 86 secured to one of the shafts 31. The energizing circuit for the magnetic clutch 27 and the holding circuit for the switch 51, having been closed, such 15 magnetic clutch 27 will remain closed until the energizing circuit for the winding 71 is broken by the engagement of the lever 84 with the cam 86. It is understood, of course, that as soon as the inner reaches of the end- 20 less conveyor chains 23 have started upward and the pallets 43 moved out of engagement with the arm 53, that such switch will return to its former position, or in position to again close a brake point in the circuit for the clutch 25 48 and brake 49 associated with the endless conveyor 45. The above sequence of operations will be continued until all of the angle irons 24 on the inner reaches of the endless conveyor chains 23 are filled with loaded 30 pallets 43.

On the cross frame member 14 and 15, are arranged pairs of bearings 87, in which pairs of bearings are rotatably mounted shafts 88. Secured to the cross frame members 15 are 35 pairs of bearings 89 and in such bearings are rotatably mounted shafts 90. On the shafts 88 and 90 are pairs of alined sprockets 91 and over such alined sprockets run endless conveyor chains 92, such endless conveyor chains being provided at intervals with cross bars 93 of angle iron or other suitable devices. The inner reaches of the pairs of 40 endless conveyor chains 92 are located considerably inside the limits of the inner reaches 45 of the endless conveyor chains 23, for a purpose to be hereinafter described. Also secured to each of the shafts 90 is a sprocket 94 which is in alinement with a corresponding sprocket 95 secured to the shafts 17 and over 50 the aligned sprockets 94 and 95 run sprocket chains 96 and by means of which intermittent rotary motion is transmitted to the shafts 88 and 89 by the shafts 17 and, therefore, by means of which intermittent step-by-step up- 55 ward movement of the inner reaches of the endless conveyor chains 92 is obtained. The movement of the conveyor chains 92 is in synchronism with the movement of the endless conveyor chains 23. Pivotaly mounted on the 60 cross frame 14 is a weighted member 108 provided with a rotatably mounted sprocket 109 that engages with the sprocket chain 96 and acts as a tension member therefor.

The mechanism above described is prefer- 65 ably located within a shed or other structure

and within such shed is located a traveling crane 98 provided with wheels 99 that run on tracks 100 suitably supported and as in the usual custom. On top of the crane 98 are tracks 101 on which run wheels 102 supporting a rectangular frame 103 carrying power lifting mechanism 104 and from which is suspended, by the four-point suspension means 105, a lifting device comprising a rectangular framework composed of outer U-shaped members 111 and centrally arranged channel members 112 tied together in the usual manner by strengthening bars or struts 113. Secured to the top end of the members 111 and spaced apart, but arranged parallel to each other, are laterally extending members 114, these members being provided at their outer free end with shackles 115, while the upper end of the members 111 are provided with shackles 116. The shackles 115, 116 act as means for attaching the framework to the four-point suspension means of the crane above described. Rotatably mounted on stub shafts 117, secured to the members 114, are rollers 118 and these rollers are adapted to engage with angle irons 119 secured to a skeleton platform 120 built onto the rectangular frameworks 11 on the side thereof remote from the driving mechanism associated with the motor 26. The endless conveyor chains 92 are so timed with relation to the endless conveyor chains 23 that the lowermost opposing angle irons 93 are brought into alinement with the angle iron tracks 119 at a time when the inner reaches of the endless conveyor chains 23 are filled with 100 pallets 43 of brick 44 and at which time it is obvious that the rectangular frame 111, together with the laterally extending pieces 114, may be moved into the limits of the frame members 11, or from the position shown in 105 Fig. 7 in dot and dash lines, to the position shown in full lines in said figure. Secured to the members 111 laterally extending therefrom and arranged parallel to each other, are lifting fingers 122, there being a pair of each of such lifting fingers 122 in horizontal alinement with each other, as there are pairs of opposed angle iron members 124, and the distance apart of the lifting fingers 122 is equal to the distance apart of the angle irons 24. 110

If the sequence of operations above described have been repeated until the space between the inner reaches of the endless conveyor chains 23 are filled with pallets 43, loaded with brick 44, the person operating the 115 lifting crane 98 may, and should, operate the crane so as to bring the frame 111 with associated lifting fingers 122 from the position shown in full lines in Fig. 6 to the position shown in dotted lines in said figure, with the 120 wheels 99 on such members 114 engaging with the angle irons or tracks 119, and after passing off the tracks 119, engaging with the angle irons 93 on the endless conveyor chains 92, which, as has been described above, are 125 130

brought into alinement with the tracks 119 at this particular point in the operation of the device.

By referring now to Fig. 9, it will be noted that while the pallets 43 rest on the angle irons 24, that the lifting fingers 122 are a considerable distance below the bottom face of such pallets, and as the sequence of operations above described is continued, the endless conveyor chains 92 will move upward, lifting the entire mechanism, comprised of the frame members 111, lifting fingers 122 and members 114, and the fingers 122 will engage with the bottom face of the pallets 43, as clearly shown in Fig. 10, whereupon, the operator of the crane will operate the crane 98 so as to move the now-loaded carrier 111 from the position shown in full lines in Fig. 7, to the position shown in dotted lines in such figure, where it will be obvious that the load of pallets 43 with the load of bricks 44 thereon, are moved from the collecting device above described. The operator may now move the crane to any part of the machine or to any other part of the works desired, where the load of bricks may be placed into a drier direct or into a collecting station that may afterward be placed in the drier.

Having thus described my invention, what I claim as new is:

1. In a device of the kind described, the combination of a pair of endless conveyors, having the inner reaches thereof arranged parallel to but spaced apart from each other, and lying in substantially vertical planes, means secured to said endless conveyors for supporting pallets of brick in substantially horizontal planes, operating means for said endless conveyors for operating the same intermittently by a step-by-step movement, and a second pair of endless conveyors arranged above the first said pair and having the inner reaches thereof operable in the same direction and at the same speed and in synchronism with the first said pair, whereby the unloading of the pallets from the endless conveyors is facilitated.

2. In a device of the kind described, the combination of a pair of endless conveyors having the inner reaches thereof arranged parallel to, but spaced apart from each other, and lying in substantially vertical planes, a horizontal conveyor associated with said pair of endless conveyors and having its delivery end located adjacent to the lower end of the upper reach of said pair of conveyors, controlling means for all of said conveyors, said controlling means being operable by the movement of the pallets of brick to throw 60 into operation either the endless conveyor or the pair of endless conveyors.

3. In a receiving station, the combination of a collecting device, means for intermittently feeding the collecting device by a step-by-step movement, a feeding device for feed-

ing a plurality of articles in succession to the collecting device, and automatic controlling means for the feeding device and collecting device operated by engagement of the articles to be fed.

4. In an improved receiving station, the combination of means for receiving a plurality of pallets carrying articles to be dried and arranging the same in vertical tiers, means for moving the receiving device intermittently by a step-by-step movement as pallets are fed thereto, a feeding device for feeding the pallets to the receiving device, said feeding device and receiving device being operated in synchronism with each other, and automatic controlling means therefor controlled by the engagement of the pallets.

In testimony whereof, I have signed my name to this specification.

CLAUD E. FULLER.
